UNITED STATES PATENT OFFICE.

HENRY CHARLES JENKINS, OF LONDON, ENGLAND.

ELECTROLYTIC CELL.

1,410,681.

Specification of Letters Patent. Patented Mar. 28, 1922.

Application filed June 10, 1919. Serial No. 303,113.

To all whom it may concern:

Be it known that I, HENRY CHARLES JENKINS, a subject of the King of England, residing at 816 Salisbury House, London 5 Wall, E. C., London, England, (whose post-office address is 816 Salisbury House, London Wall, E. C., London, England,) have invented certain new and useful Improvements in and Relating to Electrolytic Cells, 10 of which the following is a specification.

This invention relates to improvements in electrolytic cells, the object being to control the discharge from the cells by means of the feed of the electrolyte into the cell chamber 15 or by means of any other liquid supply such as does not pass as a feed supply into the cell chamber.

According to this invention the control is effected by a rise in level in a feed tank when 20 electrolyte or other liquid is fed from an external source.

The feed tank communicates with a second chamber into which some of the feed liquor can pass and repass freely. This 25 chamber has no other outlet, but contains within it a float which follows the rise in level above mentioned, rising when "feed" liquor is applied and falling as the "feed" diminishes.

30 The float can be suitably and adjustably weighted so as to follow the changes of level in the feed tank by a greater or lesser amount as may be desired, rising later and falling earlier according as the weights are increased.

The second chamber, which as well as the float is preferably of annular form, contains a tube the interior of which is quite cut off from the interior of the chamber itself 40 but is in communication with the liquid to be discharged.

Within the tube is a stem which is connected to the top of the float and is suitably guided and carries at its lower end a valve 45 resting on a seating thereby closing the tube until the valve is lifted.

Normally the liquid is discharged from the cell by overflow over a separate adjustable weir. The lifting of the valve allows 50 the discharge of some part, or the whole, of the cell independently of the overflow discharge over the weir.

Frictional resistances are inserted in the 55 pipes by suitably restricting their diameters or the amount of discharge can be varied by constricting the discharge pipe as by the

insertion of different stoppers each with a different sized perforation.

In the accompanying drawings—

Fig. 1 is a section on an enlarged scale 60 taken on the line 1—1 of Fig. 2.

Fig. 2 is a part plan of an electrolytic cell showing the present invention applied thereto, and

Fig. 3 is a vertical section looking in the 65 opposite direction to the view shown in Fig. 1, and showing in dotted lines the cell and its connection with the discharge tank; and

Fig. 4 is a section taken on the line 4—4 of Fig. 3. 70

In the drawings, A represents the body of the cell, B the feed pipe communicating with the electrolytic cell and connected by a branch pipe B' with the feed tank B². C is a discharge pipe communicating by means 75 of a branch C⁶ with the cell A and connected by the branch C' with a tank C² in which the normal level of the liquid to be discharged is controlled by a separate weir C⁴ of any known type, and in any suitable part 80 of the cell. C⁵ represents the discharge level of the weir C⁴ and is the level to which the liquid will rise in the tank C² when the cell is in normal working with the discharge valve D² closed. The rise in level of the 85 liquid in the feed tank B² when fed thereto will automatically discharge the contents of the tank C² by means of a float actuated valve such as is hereinafter described.

The feed tank B² communicates by means 90 of a branch B³ with a chamber D containing a float D' connected to a valve D² in an outlet pipe D³ communicating by a branch C³ with the tank C².

In the example shown both the chamber D 95 and the float D' are of annular form and concentrically disposed around a central tube D⁴ which is entirely cut off from the feed tank B² and float chamber D and forms a continuation of the weir tank branch C³. At 100 its lower end the tube D⁴ carries or is formed integrally with the outlet pipe D³ having a seating for the valve D². The valve is attached to a stem D⁵ which passes through an india-rubber disc in the upper closed end D⁶ 105 of the tube D⁴ and is adjustably secured to the float D' by the nuts D⁷.

It will be obvious that as the chamber D is in communication only with the feed tank B² the liquid level in the latter will be reproduced in the former and the float will 110 follow the rise and fall of the liquid in the

feed tank. As previously stated this feed level will be governed by frictional resistances of any known form adjusted in the feed pipes in any part of the cell or by restricting their diameters by any suitable means. In the example shown, the branch pipe B' is of smaller diameter than the branch pipe B^2 which opens communication between the feed tank B^2 and the float chamber D , consequently the liquid fed into the feed tank through the feed aperture B^4 will rise in the tank B^2 before passing away through the constricted pipe B' to the cell and this rise in level in the tank B^2 will actuate the float and open the valve D^2 to discharge the contents of the tank C^2 and also of the cell A through the pipe C^6 so long as the level in the feed tank B^2 is sufficiently high to raise the float D and open the discharge valve D^2 .

Having fully described my invention, what I claim and desire to secure by Letters Patent is:—

1. An electrolytic cell wherein a discharge of liquid from a tank in communication with the cell is automatically effected by the rise in level of the feed of the liquid supply in a separate feed tank connected with the source of supply and having a restricted outlet leading to the cell.
2. An electrolytic cell wherein a discharge of liquid from a tank in communication with the cell is automatically effected by a float which opens or closes a valve in the discharge pipe, said float being operated by the rise in level of the feed of the liquid supply

in a separate feed tank connected with the source of supply and having a restricted outlet leading to the cell.

3. An electrolytic cell comprising a tank in communication with the interior of the cell, a discharge pipe, a pipe opening communication between said tank and said discharge pipe, a valve in said discharge pipe, a float connected to said valve, a chamber containing said float, a feed tank connected with a source of liquid supply, and with the interior of the cell by a restricted outlet, and a pipe opening communication between said float chamber and said feed tank.

4. An electrolytic cell comprising a tank in communication with the interior of the cell, a discharge pipe, a pipe opening communication between said tank and said discharge pipe, a valve in said discharge pipe, an annular float connected to the stem of said valve, an annular chamber containing said float, a central tube in said chamber around which the float is concentrically arranged and in which the valve stem is located, a feed tank connected with a source of liquid supply, and with the interior of the cell by a restricted outlet, and a pipe opening communication between said float chamber and said feed tank.

In testimony whereof I have hereunto set my hand in presence of two subscribing witnesses this 21st day of May, 1919.

HENRY CHARLES JENKINS.
